UNITED STATES PATENT OFFICE.

JOE DE GROOTE, OF PECATONICA, ILLINOIS.

BELT BUCKLE.

Application filed October 26, 1923. Serial No. 670,912.

To all whom it may concern:

Be it known that I, JOE DE GROOTE, a citizen of the United States, residing at Pecatonica, in the county of Winnebago and State 5 of Illinois, have invented new and useful Improvements in a Belt Buckle, of which the following is a specification.

This invention relates to a new and improved buckle and more particularly to a belt buckle equipped with means to engage a trousers button and a hook adapted to embrace the overlapping edge of the waist band of the trousers so as to maintain the buckle in place and at the same time to 10 prevent the waist band from becoming unfastened.

The main object of the invention is to provide a device of the above character that is simple in construction, strong and durable and which, it is believed, may be manufactured at a reasonably low cost.

Various other objects and advantages of my invention will become apparent during the continuance of the following description.

In the drawings:—

Fig. 1 is a view in rear elevation showing my invention in its preferred embodiment and as carried by a belt of conventional construction.

Fig. 2 is a top view of a portion of the waist band of a pair of trousers showing my invention, partly in section, operatively associated therewith.

Fig. 3 is a view in horizontal cross section taken on line 3—3 of Fig. 1.

In the drawings 10 designates a buckle of substantially conventional form which is carried by a belt 11 of the usual and well known construction. At one end the buckle 10 is provided with a hook member 12 which is preferably made of wire and which has its ends secured to the upper and lower flanges thereof as clearly shown in Fig. 2. It will be observed in this connection that the hook member 12 lies in a plane behind the body of the buckle so as not to obstruct the passage for the free end of the belt, and at the same time to assume a position whereby it

may be conveniently brought in operative 50 relation to the overlapping edge of a portion of the trousers such as will be herein-after more fully described.

Adjacent the other end of the buckle and on the inside edge thereof I also provide a 55 metallic clip 13 whose upper end is slotted as at 14 so as to form a clasp that may be brought into engagement with the shank of a trousers button and thus help maintain the buckle in place as well as prevent 60 accidental displacement of that portion of the trousers held by the button.

To illustrate more clearly the application of my invention I have shown, in Fig. 2 the overlapping portions 15 and 16 of the 65 waist band of a pair of trousers which overlapping portions are fastened together by means of a button 17. When the belt is arranged in place the buckle 10 assumes a position adjacent to the overlapping edges of the 70 trousers so that the clip 13 can be engaged with the button 17 and the hook 12 arranged over the edge of the overlapping portion 15 of the trousers as shown. From this it will be observed that the accidental displacement 75 of the overlapping edges 15 and 16 will be prevented and also that the buckle 10 will be firmly held in position.

From the foregoing it is believed that the advantages and novel features of my invention will be readily understood, and therefore further detail and description is deemed unnecessary.

What is claimed is:—

1. A belt buckle including a hook member 80 carried at one end and adapted to overlie the overlapping edge of the waist band of a pair of trousers and a clasp carried adjacent the other end adapted to be engaged with the button that secures the overlapping edge of the trousers in place.

2. A belt buckle including a trousers engaging hook carried at one end and lying in a plane behind the buckle, and a button engaging clasp carried on the back of the 85 buckle and spaced adjacent the other end thereof substantially as described.

JOE DE GROOTE.
